United States Patent Office.

EDWIN ALLEN, OF NORWICH, CONNECTICUT.

Letters Patent No. 92,558, dated July 13, 1869; antedated July 3, 1869.

IMPROVEMENT IN ENVELOPE-GUMMERS.

The Schedule referred to in these Letters Patent and making part of the same.

To all whom it may concern:

Be it known that I, EDWIN ALLEN, of Norwich, in the county of New London, and State of Connecticut, have invented a new and useful Improvement in Envelope-Gummers, of which the following is a full, clear, and exact description, reference being had to the accompanying drawing, forming part of this specification, and in which—

Figure 1 represents a top view or plan of an envelope-gummer, constructed in accordance with my improvement, and as resting upon a pile of envelopes;

Figure 2, a transverse vertical section of the same; and

Figure 3, an under view or inverted plan of the gummer.

Similar letters of reference indicate corresponding parts.

My invention relates to automatic devices for gumming the flaps or folding portions of envelopes in which the gum or adhesive fluid is passed on to the envelope through an opening or orifice, of a shape corresponding to the surface to be gummed.

My improvement consists in providing the gum-box spout, which conveys the gum to the envelope, with an outside rubber cloth, or other like soft and elastic packing, arranged to surround said spout at its lower end, and to project below or beyond it, so as to rest on the envelope in a soft and easy manner, conforming itself to inequalities in the surface of the pile, and whereby the gum may be allowed to pass uninterruptedly from the box or hopper without smearing more of the envelope than is required, and so that on drawing the envelope from under the gummer, the elastic lip formed by the outside packing, acts as a brush, to remove surplus gum from the envelope.

Referring to the accompanying drawing—

A represents a gum-box or hopper, in which the gum or adhesive fluid to be used is placed.

Said box is free to slide down guide-rods *a a*, so as to bear or rest, through its spout B, or rather, packing C, surrounding the latter, on the pile of envelopes D, which rest on a bed, or table, S, and to follow the same as they are drawn, one by one, from under it.

The spout B, which may be made of thin sheet-metal, is of any suitable shape and size, corresponding to the envelope-surface requiring to be gummed, and is in open communication with an aperture or orifice, E, of similar configuration.

The soft and elastic, or flexible packing C, which is arranged on the outside of the spout B, projecting below it, and encompassing its sides and ends, and which may be held to its place by clamps F F, I prefer to make of rubber cloth, or other like material, doubled or folded, so as to present a close, rounded lower edge, made up of two thicknesses of the material.

To this end, said outside packing may be made of tubing, of suitable flexible material, which admits of the reversal of the packing when the lower edge becomes worn.

By employing a folded packing, arranged to present a close, rounded edge, I find that it not only forms a soft and elastic lip that conforms itself to any inequalities or irregularities in or on the pile of envelopes D, situated below it, and retains the gum issuing through the orifice E, but that, in drawing the envelopes one by one from under it, to effect the gumming of them in succession, it acts as a more effectual wiper or leveller of the gum on the envelopes, sweeping the surplus gum from off the one envelope as it is withdrawn on to the next envelope below it, and readily springing back when bent by the draught of the envelopes in succession from under it, or otherwise retaining its erect position, to insure a proper restriction of the gum on each envelope.

A packing composed of a single thickness of material might be used instead, but the same is not only more liable to spring or be bent from its erect position, but, in being bent by the draught of the envelopes from under it, presents an irregular and sharp, or angular sweeping-edge, which effects a less perfect levelling-action on the gum, does not secure the same protection against leakage past the edges of the packing, and less readily springs back to its position, or more readily takes "set," as induced by the draught of the envelopes from under it, than does the packing made of a double thickness of material, and presenting a rounded lower edge, which, while moderately flattening, by the weight of the gum-box and its contents, retains the same levelling-action or effect on the gummed surface of the envelope, free from all sharp, angular presentation throughout the entire draught of each envelope in succession from under it.

The envelopes D may be piled and withdrawn, one by one, from under the gummer, either by hand or by any suitable mechanism for the purpose.

When not using the gummer, it may be left in water, to prevent clogging or hardening of any remaining gum on it or its packing.

What is here claimed, and desired to be secured by Letters Patent, is—

The arrangement of a soft and elastic or flexible packing around the outside of the spout to the gum-box or hopper, and so as to project below it, substantially as specified, and for the purpose herein set forth.

EDWIN ALLEN.
